UNITED STATES PATENT OFFICE.

HARRY HARRISON, OF LOWELL, MASSACHUSETTS, ASSIGNOR TO C. G. SARGENT'S SONS CORPORATION, OF GRANITEVILLE, MASSACHUSETTS, A CORPORATION OF MASSACHUSETTS.

MEANS FOR PREVENTING LODGMENT AND MATTING OF FIBROUS MATERIAL ON CONVEYERS.

1,235,027.

Specification of Letters Patent.

Patented July 31, 1917.

Application filed November 8, 1916. Serial No. 130,253.

To all whom it may concern:

- Be it known that I, HARRY HARRISON, a citizen of the United States, residing at Lowell, in the county of Middlesex and 5 State of Massachusetts, have invented a new and useful Means for Preventing Lodgment and Matting of Fibrous Material on Conveyers, of which the following is a specification.
- 10 This invention, although capable of general use, is particularly adapted for the cleaning of wire cloth and similar conveyers for carrying wool and other fibrous materials.
- 15 The principal object of the invention is to provide for freeing from fibers and foreign matter the openings in the wire cloth or other porous material of which the conveyer is made by preventing the initial lodgment and matting of the lint and the like in the carrying surface. In this way a free 20 passage for air is provided through the conveyer so as to increase the efficiency for drying purposes. Further objects and advantages of the invention will appear hereinafter.

Reference is to be had to the accompanying drawings, in which—

Figure 1 is an elevation of one form of 30 wool drier with the front side removed showing the conveyer and a preferred means for cleaning the same, and

Fig. 2 is a sectional view on the line 2—2 of Fig. 1.

35 The invention is shown as applied to a well-known type of wool drier in which the wool is fed down the chute 10 on a flat wire cloth endless apron or conveyer 11 carried by drums 12 and is continuously fed out on 40 a plate 13 from which it drops. Blowers 14 are shown for blowing the warm dry air through the conveyer to expedite the drying operation.

45 This invention provides for keeping the interstices of the apron or conveyer free from fibers and foreign materials so as to afford at all times a free circulation of air through the conveyer. This is particularly important in an endless conveyer because 50 there are two strands, the lower one of them coming between the blowers and upper strand which supports the material to be dried. It is well-known that conveyers,

especially in the form of wire cloth, fill up with lint and other fibrous materials so as 55 to form a mat. This affords, in the form shown in the drawings, two flat partitions for interfering with the flow of the hot air through the wool or other material to be dried. Each one of these partitions tends 60 to deflect the hot air around the sides and ends of the conveyer, and thus materially reduces the efficiency not only on account of passing the hot air out of contact with the wool, but also by tending to obstruct 65 the current of the air and make it harder to force it through the machine.

According to the present invention this objection is done away with in an extremely simple manner. Two pipes 15 are shown 70 for introducing steam or air under pressure between the strands of the conveyer. These pipes are provided with a plurality of nozzles 16. They are shown as in two series, one pointing upwardly directly under the 75 upper strand of the conveyer and the other pointing downwardly directly over the lower strand. The air or steam therefor is forced against the inner side of the conveyer outwardly so as to force the lint back the way 80 in which it came and thus easily dislodge it from the conveyer. It is to be noted that the jets extend practically across the conveyer at both points and thus clean it all the way across.

85 It will be understood, of course, that the upper one blows the lint up into the wool that is being carried off so that it has a tendency to be removed from the drier with the product thereof and cannot become 90 lodged initially.

It will be understood also that if desired the air under pressure can be heated, thus assisting the drying operation in the case of the upper series of jets. This method 95 can be used whenever necessary, or if desired it can be used continuously, thus keeping the conveyer free from lint and not at any time allowing it to collect. I prefer to carry the invention out in the latter way 100 and when that is done only a low pressure need be used.

105 Although I have illustrated and described only a single embodiment of the invention and shown it as applied only to a single type of conveyer, yet I am aware of the fact that

the invention can be carried out in other ways and that it can be applied to a large number of types of conveyers both reciprocating and endless without departing from 5 the scope of the invention as expressed in the claim. Therefore I do not wish to be limited to all the details of construction herein shown and described, but what I do claim is:—

10 In a machine of the class described, the combination of an endless screen conveyer

having a substantially flat conveying surface with two transverse pipes located between the strands thereof and in parallel planes, one near the operating strand and the other near 15 the idle strand, each of said pipes having jet openings directed toward the adjacent strand of the conveyer for blowing air or steam against the same.

In testimony whereof I have hereunto 20 affixed my signature.

HARRY HARRISON.
